HEATER FOR FLUIDS

Kurt W. Fleischer, Philadelphia, Pa., assignor to
 Selas Corporation of America, Philadelphia,
 Pa., a corporation of Pennsylvania

Application September 7, 1944, Serial No. 552,943

4 Claims. (Cl. 122—356)

1

This invention relates to a heater for fluids, and it is an object of the invention to provide an improvement for effecting positive control of the heating of fluids in one or more tube banks through which fluid is circulated.

The above and other objects and advantages of the invention will become apparent from the following description taken in conjunction with the accompanying drawings forming a part of this specification, and of which:

Fig. 1 is a vertical cross sectional view more or less diagrammatically illustrating an embodiment of the invention;

Figs. 2 and 3 are fragmentary views, taken at lines 2—2 and 3—3 of Fig. 1, respectively, to illustrate the invention more clearly; and

Fig. 4 is a vertical sectional view similar to Fig. 1 illustrating another embodiment of the invention.

Referring to Fig. 1, the invention is shown applied to a heater 10 having a floor 11 and side walls 12 and 14 including vertical portions 15 and 16, sloping wall portions 17 and 18, and straight wall portions 19 and 20 which extend upwardly from the sloping wall portions. The floor 11 and side walls 12 and 14 are formed of suitable refractory material disposed within a framework or outer shell (not shown) which is supported on a foundation in any well known manner.

The floor 11 and side walls 12 and 14 form a heating chamber 21 which is divided into two cells 22 and 23 by a refractory wall 24 which is centrally disposed between the side walls 12 and 14 and extends upwardly from the floor 11 a distance substantially equal to the height of the side wall portions 15 and 16.

A bank of fluid conduits is located in each of the cells 22 and 23 adjacent the side wall portions 15 and 16, respectively. The tube banks 25 and 26 comprise single rows of horizontally disposed conduits 27 and 28, respectively, which are located one above the other and connected at their ends to provide two elongated paths of flow for the fluids to be heated.

Above the tube banks 25 and 26 and in the space 29 between the sloping wall portions 17 and 18 are located two banks of fluid conduits 30 and 31, respectively. The tube banks 30 and 31 comprise horizontally disposed conduits 32 and 33 which are connected at their ends to form two elongated paths of flow for the fluids to be heated.

In accordance with this invention, the side wall portions 15 and 16 are provided with spaced baffles or shields 34 which extend or project in-

wardly from the inner surfaces of the side wall portions 15 and 16 toward the tube banks 25 and 26 to subdivide the cells 22 and 23 into a plurality of heating zones 35 and 36, respectively; and 5 heat producers or burners 37 are provided at the side wall portions 15 and 16 for independently firing such heating zones.

The spaced baffles or shields 34 are shown as horizontally disposed ridges extending alongside 10 of and co-extensive with the lengths of the conduits 27 and 28. The apices 39 of the sloping sides 40 of the ridges 34 are located closely adjacent to and midway between adjacent conduits 27 and 28 in each of the tube banks 25 and 26. 15 With this arrangement each heating zone 35 and 36 is intimately associated with a definite part or batch of tubes of the tube banks 25 and 26. The burners 37 are distributed at the side wall portions 15 and 16 in any suitable manner, and, 20 as shown most clearly in Fig. 2, may be arranged in staggered relation so that a horizontally disposed row of burners is associated with each heating zone 35 and 36. Each burner is formed with a passage within which is disposed a burner tube 25 or sleeve 41. As shown in Figs. 1 and 3, the outer ends of sleeves 41 are connected by pipes 42 to horizontally disposed manifolds 43 which in turn are connected to a larger vertically disposed manifold 44 to which fuel is delivered through 30 a conduit 45 from a suitable source of supply. A main control valve 46 is connected in conduit 45, and valves 47 are provided to control the pressure and rate at which the fuel is supplied to the horizontal manifolds 43. The supply of 35 the fuel for each burner 37 may be individually controlled by valves 48 connected in the pipes 42.

Although not to be limited thereto, the burners 37 may be of the kind described and illustrated in Hess Patent No. 2,215,079, granted September 40 17, 1940 and assigned to the same assignee as this application. The burners 37 are fully described in the aforementioned Hess patent which may be considered as being incorporated in this application, and, if desired, reference may be 45 had thereto for a detailed description of the burner structure.

The burners 37 may be operated with a suitable fuel, such as a mixture of a gas and air, for example, which is supplied to each of the 50 burners and subdivided into a plurality of gas streams by distributors or tips 49 fixed to the inner ends of the sleeves 41 which terminate at cup-shaped spaces 50. Substantially complete combustion of the fuel is effected in the cup-shaped spaces 50, so that flame impingement

of the conduits 27 and 28 is avoided. The refractory wall surfaces of the cup-shaped spaces 50 are heated to incandescence and constitute high temperature zones or regions from which heat is radiated to the conduits 27 and 28. The heated products of combustion formed in the cup-shaped spaces 50 heat to incandescence the inner surfaces of the wall portions 15 and 16 surrounding the cup-shaped spaces and also the sloping sides 40 of the baffles 34.

In the heater 10 shown and just described, one stream of fluid to be heated may enter the top part of tube bank 30 and pass from the bottom part thereof to the tube bank 25 for downward flow to the latter. Similarly, another stream of fluid to be heated may enter the top part of tube bank 31 and pass from the bottom part thereof to the tube bank 26 for downward flow through the latter. Heat is radiated directly to one side of the tube banks 25 and 26 from the cup-shaped spaces 50, inner wall surfaces surrounding the cup-shaped spaces, and the sloping walls 40 of the baffles. Both sides of the central refractory wall 24 are heated to a highly radiant condition by heat radiated from the combustion gases, the cup-shaped spaces 50, inner wall surfaces surrounding the cup-shaped spaces, and sloping walls 40; and reflected radiant heat is transmitted from the central wall 24 to the opposite sides of the tube banks 25 and 26.

The hot combustion gases formed in the cup-shaped spaces 50 and discharged from the cells 22 and 23 pass over the conduits 32 and 33 and inner surfaces of the sloping wall portions 17 and 18 to effect heating of the tube banks 30 and 31 before being discharged from the heater 10.

While a part of the heating of the tube banks 25 and 26 is effected by the hot combustion gases formed in the cup-shaped spaces 50 of the heating zones 22 and 23, these tube banks at one side are heated predominantly by heat radiated directly from the incandescent side wall portions 15 and 16, and at the other side by heat re-radiated from the unfired central wall 24, as described above. Hence, by regulating the rate of supply of fuel to the burners 37 and the heat output of the burners, it is possible to obtain positive control of the heating of the tube banks 25 and 26 throughout the entire path of fluid flow provided by the conduits 27 and 28.

In the embodiment shown in Fig. 1, for example, five conduits 27 and 28 are associated with each heating zone 35 and 36, respectively. The apices 39 of the baffles 34 terminate midway between adjacent conduits 27 and 28 in each of the tube banks, so that the baffles 34 effectively shield the burners 37 between adjacent heating zones. By way of illustration and without limitation, the distance from the inner surfaces of the side wall portions 15 and 16, that is, the outer extremities of the cup-shaped spaces 50, to the conduit centers may be about 14 inches when conduits 27 and 28 approximately four inches in diameter are employed; and the apices 39 may be midway between adjacent conduits in the tube banks 25 and 26 and approximately three inches from the vertical planes of the conduit centers.

If desired, the extreme ends of the baffles 34 may project even closer to the centers of the tube banks than shown in Fig. 1. In any event, the baffles 34 are associated with a definite number of conduits in each tube bank and the heating of each group of conduits 27 and 28 directly opposite one of the heating zones can be positively controlled by regulating the burners 37 provided to

fire each such heating zone. Thus, as the fluid to be heated flows downwardly through the tube banks 25 and 26, for example, the desired heating of the fluids may be effected in the five uppermost conduits 27 and 28 by regulating the burners 37 in the top rows at the side wall portions 15 and 16. Similarly, as the fluid to be heated passes through successively lower heating zones 35 and 36, the heating of the conduits 27 and 28 associated with each successive heating zone can be positively and accurately controlled by proper adjustment of the burners 37 provided for firing each heating zone.

The heater 10 is extremely flexible in operation. This can best be illustrated by assuming that in a particular instance it is desired to cut out the lowermost or bottom rows of burners 37 in each of the side wall portions 15 and 16, and that it is necessary to effect the same heating of the upper parts of the tube banks 25 and 26 that is accomplished when the bottom or lowermost heating zones 35 and 36 are being operated. In such case it is a simple matter to increase the heating effect produced in the upper or top heating zones 35 and 36 by increasing the heat output of the burners 37 associated with such heating zones, thereby compensating for the reduction in heating resulting from the cutting out of the lowermost rows of burners 37.

It may also be desirable to provide a heater embodying the invention in which the central refractory wall 24 is omitted. Such a modification is shown in Fig. 4 in which parts similar to those illustrated in Fig. 1 are designated by the same reference numerals. In the heater 10a of Fig. 4, heat is radiated directly to one side of the tube banks 25 and 26 from the side wall portions 15 and 16 adjacent to which the tube banks are located. Thus, heat is radiated to one side of the tube bank 25 from the side wall portion 15 which includes heat radiated from the cup-shaped spaces 50, the inner surfaces of the side wall portion 15 surrounding the cup-shaped spaces, and the sloping sides 40 of the baffles 34. Similarly, heat is radiated directly to one side of the tube bank 26 from the inner surfaces of the side wall portion 16.

Heat is also radiated to the opposite sides of the tube banks 25 and 26 from the inner surfaces of the side wall portions 16 and 15, respectively. Thus, the side of the tube bank 25 facing the side wall portion 16 is heated by heat radiated from such side wall portion, and the side of the tube bank 26 facing the side wall portion 15 is heated by heat radiated from the latter. The same positive control of the heating of the tube banks is effected in Fig. 4 as in the embodiment first described, and, since the modification of Fig. 4 is generally the same as the embodiment of Fig. 1 with the central refractory wall 24 omitted, further description will not needlessly be repeated here.

In view of the foregoing, it will now be understood that an improved heater for fluids has been provided for obtaining positive heat control over an entire tube bank. While the heater of the invention may be employed for heating all kinds of fluids, it is especially useful for heating hydrocarbons to the high temperatures required for thermal or catalytic conversion. While specific paths of flow for fluids to be heated have been described above, it is to be understood that the tube banks, as well as the conduits in the individual tube banks, may be connected in any desirable manner to provide one or more paths of

flow for fluid to be heated. Irrespective of the manner fluid flows through the tube banks, the flexibility of the heater of the invention and the positive heat control of all parts of each tube bank enables a wide variety of heating curves to be obtained depending upon the character of the fluid undergoing heating.

The positive heat control described can be obtained when the fluid conduits are disposed vertically instead of horizontally, as shown and described herein. When the fluid conduits of a tube bank are vertical, the baffles or shields are disposed vertically at the inner surfaces of the heater walls. The refractory baffles may be of any desired shape and formed of ceramic material or alloys capable of withstanding high temperatures.

Although several embodiments of the invention have been shown and described, it will be apparent to those skilled in the art that modifications may be made without departing from the spirit and scope of the invention, as pointed out in the following claims.

What is claimed is:

1. A heater for fluids comprising structure forming a radiant heating chamber comprising side walls including spaced vertical side wall portions and wall portions sloping upwardly and inwardly from the side wall portions to form a space having an opening at the upper part thereof, banks of fluid conduits disposed in the chamber adjacent the vertical side wall portions, spaced baffles extending parallel to the tube banks and for the full length thereof at the inner surfaces of the vertical side wall portions and projecting toward the tube banks, said baffles being arranged in such a way that the chamber is divided into a plurality of parallel heating zones, means for independently firing the heating zones comprising a row of radiant burners distributed at the wall between each pair of baffles, means to adjust simultaneously the burners of each row, and a bank of fluid conduits disposed in the space between the sloping wall portions.

2. A heater for fluids comprising structure including spaced apart side walls forming a radiant heating chamber, a wall disposed between the side walls for dividing the chamber into a plurality of cells, a bank of horizontally extending fluid conduits disposed in each cell adjacent to one of the side walls, spaced baffles at the inner surfaces of the side walls projecting toward the tube bank and parallel thereto for the major portion of the

length thereof, said baffles being arranged in such a way that the cells are divided into a plurality of parallel heating zones, means for independently firing the zones comprising a row of radiant burners distributed at the sidewalls in each zone, and means by which all the burners in each row can be adjusted at one time.

3. A heater for fluids comprising structure including a wall forming a radiant heating chamber, a bank of tubes adjacent to the wall and through which fluid is adapted to flow, means including a plurality of rows of radiant burners distributed at the wall for firing the chamber, high temperature refractory means extending parallel to the tubes and between the bank of tubes for the full length thereof and the wall to separate the rows of burners into groups from each of which radiant heat is transmitted substantially entirely to a particular batch of tubes in the tube bank, and means by which all of the burners in each group can be adjusted at one time to selectively control the heating of fluid flowing through each batch of tubes.

4. A heater for fluids comprising structure including a wall forming a radiant heating chamber, a bank of horizontally disposed fluid conduits in the chamber adjacent to the wall, spaced baffles extending parallel to the tubes of the bank at the inner surface of the wall and projecting toward the tube bank for the full length thereof, said baffles being arranged in such a way that the chamber is divided into a plurality of heating zones each of which is directly opposite a portion of the tube bank, means for independently firing each zone comprising a plurality of rows of burners distributed along the wall with a row between each pair of baffles for heating the wall and the baffles to a highly radiant condition, and means by which all of the burners in each row can be adjusted at one time.

KURT WM. FLEISCHER.
